UNITED STATES PATENT OFFICE.

PETER JAY SCHELB, OF FORT WORTH, TEXAS.

PLAY TOY FOR CHILDREN.

Application filed May 13, 1924. Serial No. 713,015.

My invention relates to improvement in play toys for children for a wheel connected with a push rod actuating an image, in play toys for children, where a child as it walks or runs rolls a wheel along by means of a push rod, and the image of a quadruped is actuated in a leaping manner by being connected with the push rod and the wheel.

The objects of my invention are:

10 First, to provide a toy with a natural hip movement that will be interesting for a child to play with and to provide a healthy out-door exercise. Second, to provide a toy that is durable and will be enjoyed by the 15 larger boy and girl as well as the smaller ones.

I attain these objects by the mechanism illustrated by the accompanying drawings, and as set forth in the specifications in which Fig. 1 is a perspective view, Fig. 20 2 is a plan view of same, Fig. 3 is the general contour of an integral quadruped, excepting its hind leg, which is substituted by a short link pivoted to the hip; the object of the integral contour is to provide a 25 long link connection between pivot 9 at the front foot and 12 at the hip, which gives the image a regular and natural movement at the hip. Fig. 4 is a short link about one- 30 third the length of the distance between the pivotal connections of Fig. 3, and it forms a connection between the hip and push-rod by having one end pivotally connected to the image at 12, and the other end 35 pivotally connected with the push rod at 11,

which is located a suitable distance from the wheel for the purpose set forth. Similar characters of reference are used to indicate the same parts throughout the different views in which 5 is a push-rod, 6 40 push-wheel, 7 pivot connecting wheel with push-rod, 8 is front foot of quadruped, 9 crank, 10—11 and 12 are pivotal connections.

Thus it will readily be seen, by pivotally connecting the push-rod 5 with 6 by means 45 of pivot 7, and by connecting 8 with 9—10 with 11 and 12 with 12, that as the child rolls the trundle wheel along by means of the push-rod, the crank 9 revolves around the pivot 7 and actuates the image in a leaping manner with a natural hip movement.

This device may be made of any kind of suitable material, and changes may be made in the form, and minor details of construction without departing from the spirit of 55 my invention.

What I claim is:

In a play toy of the character described a trundle wheel pivotally connected to a push-rod, an integral member having the 60 contour of a quadruped, having its front leg eccentrically connected to the wheel a link shorter than the member, said link being connected to the rear end of the member at the hip, and having its other end 65 pivotally connected with the push rod at a distance between the extreme back and forth travel of the other end of said link when actuated by said wheel.

PETER JAY SCHELB.
